UNITED STATES PATENT OFFICE.

WILLIAM J. COSTELLO, JR., OF OAKMONT, PENNSYLVANIA, ASSIGNOR TO VERONA TOOL WORKS, OF PITTSBURGH, PENNSYLVANIA, A CORPORATION OF PENNSYLVANIA.

RAIL SPRING AND METHOD OF MAKING THE SAME.

Application filed January 16, 1925. Serial No. 2,866.

To all whom it may concern:

Be it known that I, WILLIAM J. COSTELLO, Jr., a citizen of the United States, residing at Oakmont, county of Allegheny, and State of Pennsylvania, have invented a new and useful Improvement in Rail Springs and Methods of Making the Same, of which the following is a full, clear, and exact description.

10 The present invention relates broadly to rail springs, and more particularly to springs of that class generally referred to as the "leaf" type, it being designed to provide an improved spring bridging at least 15 two bolts for holding splice bars in the desired position by yielding pressure and at the same time take up wear and reduce battering of the rail ends.

I am aware that heretofore it has been proposed, as shown for example in Patents No. 1,416,152 issued May 16, 1922, and No. 1,443,160 issued January 23, 1923, to Emanuel Woodings, to provide rail springs having a compound longitudinal curvature 25 with enclosed bolt-receiving openings adjacent each end thereof. The present invention, although not limited to springs of this construction, has for one of its specific objects improvements in springs of this 30 type for the purpose of so constructing the rail springs that they will serve not only the functions referred to but also the functions of a nut lock tending to prevent any loosening of the nuts utilized for holding the 35 splice bars in position.

In the accompanying drawings, there are shown for purposes of illustration only a preferred embodiment of the present invention, it being understood that the drawings do not define the limits of the invention as changes in the construction and operation 40 therein disclosed may be made without departing either from the spirit of the invention or scope of my broader claims.

45 In the drawings:

Figure 1 is a perspective view of an improved rail spring embodying the present invention, and

50 Figure 2 is a transverse sectional view through a rail with assembled splice bars showing my improved spring in position

ready to be tightened against the side of one of the bars.

In accordance with the present invention, a rail spring may advantageously be utilized 55 which is formed of rolled spring steel and so shaped as to provide both a longitudinal and a transverse curvature, although if desired, the transverse curvature may be omitted. The longitudinal curvature is preferably 60 of a compound character, providing a central portion 2 projecting inwardly and adapted to first contact with the side of one of the splice bars, and side portions 3 extending outwardly from the central portion and then preferably inwardly to a greater or less extent adjacent the ends, in a reverse curve. The spring is also preferably 65 curved transversely so that its inner surface next to the splice bar 4 is slightly 70 concave, while the outer surface is correspondingly convex.

Experience has shown that in a rail spring of this character the greatest inward 75 bend longitudinally of the spring should be at approximately its center as shown whereby in the initial application of the 80 spring and before tightening of the parts in position the ends are in slightly spaced relation to the sides of the splice bars. The longitudinal curving of the spring may also 85 be such that when tightened in use it will take a partial permanent set by carrying the metal past the elastic limit in straightening. With such a construction, when the spring is taken off, it does not return to its original 90 shape, but assumes a configuration between such original shape and the shape assumed when in use. This has been found to add 95 materially in giving the spring its desired characteristics in holding the splice bars firmly in position and reducing battering of the rail ends.

The form of the spring illustrated in Figure 1 is of a length greater than the distance between two adjacent bolt holes in the splice bars with which it is to be used, and is formed with enclosed holes 5 adjacent its ends, these holes being formed in the side portions 3-3 between the central inward bend and the reversely bent ends and 100 preferably at the crown or high point of

such reverse bends. As shown in Figure 1, the openings are elongated, to permit relative movement with respect to the bolts 6 which are passed therethrough. Such movement occurs during the tightening of the nuts 7, it being apparent that by this operation the spring is partially flattened and thereby elongated. It will be understood that the initial positioning of the holes 5 is such that when the spring is first applied the bolts will extend adjacent the outer ends of the openings whereby the spring is free to elongate as set forth.

It will be readily apparent to those skilled in the art that under the action of the rolling stock passing over the rail joints, the rail ends, the splice bars, the springs and the retaining bolts are all subjected at the joints to severe usage. The action of the rolling stock tends to batter down not only the heads of the splice bars but also to batter down and wear away the under surface of the head of the rail in contact therewith. This soon provides room for play between the rails and the splice bars permitting the same to move slightly one with respect to the other. While this movement is to a considerable extent, and in a highly satisfactory manner, prevented by the action of the spring herein disclosed, it will be understood that the tendency to move is such as to tend to effect loosening of the nuts 7.

In order to maintain the track in the desired state of repair it is essential to prevent loosening of the nut 7. At the same time, it is not desirable from a practical standpoint to utilize separate nut locks with the springs. I have found that the spring itself may be constructed to serve the dual function of a nut lock and spring by splitting the ends as indicated in Figure 1 to form separate projections 8 and 9 on each end of the spring, similar projections preferably being on diagonally opposite corners. After the springs have been slit, preferably along lines slightly above or below the center of the corresponding opening 5, to form projections of unequal sizes, the smaller of these two projections, herein designated by the reference character 9, are bent out of the plane of the projections 8 whereby to provide oppositely disposed projecting shoulders or teeth 10 on the outer face of the spring. As clearly apparent from the showing of Figure 2 these shoulders are such that they will engage the under side of a nut 7 and tend to effectively bite into the same to prevent rotation thereof in such direction as to back the nut from the bolt. Where the spring is initially formed with a transverse curvature, the action of the biting teeth 10 is made more effective as they lie substantially in the plane of the highest portion of the bar thereby insuring contact at all times with the under

side of a nut. Where, however, the transverse curvature is omitted, the bending of one of the projections out of the plane of the other projection provides a tooth which effectively serves to prevent loosening of the nuts.

The advantages of the present invention arise from the provision of a rail spring adapted to serve the combined function of a spring and nut lock.

I claim:

1. A rail joint spring shaped to cooperate with adjacent rail bolts, said spring having at least one end thereof shaped to effectively resist loosening of a nut while permitting relatively free movement of the nut in the opposite direction to tighten the same, substantially as described.

2. A rail joint spring shaped to extend lengthwise of a rail and cooperate with adjacent rail bolts, said spring having an integral portion of the metal displaced adjacent one end to form a nut engaging tooth, substantially as described.

3. A rail joint spring shaped to cooperate with adjacent bolts, said spring having divided end portions forming spaced projections one of which is disposed out of the plane of the body of the spring to form a nut engaging tooth, substantially as described.

4. A rail joint spring shaped to cooperate with adjacent bolts, said spring having divided end portions forming projections one of which is disposed out of the plane of the body of the spring to form a nut engaging tooth, substantially as described.

5. A rail joint spring having a compound longitudinal curvature and provided with bifurcated end portions adapted to cooperate with spaced bolts, one of the bifurcations in each end being disposed out of the plane of the other bifurcation to form a nut engaging tooth, substantially as described.

6. A rail spring having both longitudinal and transverse curvatures, and provided near its ends with enclosed bolt holes, the body of the metal beyond said holes being slit to form a nut engaging tooth, substantially as described.

7. A rail spring having both longitudinal and transverse curvatures, and provided near its ends with enclosed bolt holes, the body of the metal beyond said holes being slit to form projections one of which is disposed out of the plane of the other projection to form a nut lock, substantially as described.

8. A longitudinally curved rail spring adapted to be forced against the surface of a splice bar, said spring having elongated enclosed bolt holes in its ends and having integral nut engaging means adjacent each of said holes, adapted to resist turning of a nut in one direction while permitting turn-

ing in the opposite direction, substantially as described.

9. A longitudinally curved rail spring adapted to be forced against the surface of a splice bar, said spring having elongated enclosed bolt holes in its ends and having integral nut engaging and locking means ad-

jacent each of said holes, said means comprising a tooth displaced out of the plane of the body of the spring, substantially as 10 described.

In testimony whereof I have hereunto set by hand.

WILLIAM J. COSTELLO, Jr.
